UNITED STATES PATENT OFFICE.

THOMAS CROSSLEY, OF BOSTON, MASSACHUSETTS.

METHOD OF MAKING PRINTING-BLOCKS.

Specification of Letters Patent No. 11,321, dated July 18, 1854.

To all whom it may concern:

Be it known that I, THOMAS CROSSLEY, of Boston, in the county of Suffolk and State of Massachusetts, have invented a new and useful Method of Making Blocks for Printing Woolen Goods, House-Paper, and other Analogous Articles; and I hereby declare the following to be a full, clear, and exact description of the same, reference being had

10 to the annexed drawings, making part of this specification, and which will be referred to hereafter.

Blocks for printing woolen goods have heretofore been faced with felt; the process 15 by which this has been accomplished being tedious and expensive. It has been found however that gutta percha is far superior to 20 felt as a material for forming printing surfaces, and my invention consists in an economical and expeditious method of applying the gutta percha to a wooden block, which method I will describe as follows: I take a block of maple or other suitable wood and cover its surface with fine saw kerfs *a*, 25 running at right angles to each other as seen in Figure 1, and sinking about $\frac{1}{4}$ inch more or less below the surface; this divides the surface of the block into minute quadrangular prisms; these prismatic pieces are 30 then removed from those portions of the block not covered by the figure, and are left remaining upon those portions which are covered by the figure, in a manner similar to that adopted for making blocks for 35 printing floor cloths. The gutta percha is then softened in the customary way and laid upon a flat surface; the block prepared as above is then pressed upon the gutta percha, by which means the latter is forced into the

interstices *b*, between the minute prisms 40 which compose the figure. These prisms are thus bound solidly and firmly together, and a surface is produced having all the absorbent qualities of the gutta percha and all the strength of the wood itself, while it is 45 more economically and expeditiously made than can be done by any method with which I am acquainted.

A further advantage which my block possesses results from the fact that the wood 50 of which it is composed is far less liable to warp than where felt is employed; in the latter case the moisture of the colors is allowed to pass freely through the felt to the wood, by which the latter is both warped 55 and split. Where the block is constructed with gutta percha in the manner above described, the water is effectually secluded from the wood, which is thus protected from either warping or splitting, casualties to 60 which printing blocks as heretofore constructed were more or less exposed.

I do not claim the use of gutta percha, as a material for making printing blocks, neither do I claim sawing blocks into prisms, 65 for the purpose of more easily removing those portions of the block not required for the figure, but

What I do claim as my invention and desire to secure by Letters Patent is— 70

The within described method of making printing blocks, the surface of gutta percha being applied to the surface of the wood, in the manner and for the purpose set forth.

THOMAS CROSSLEY.
